UNITED STATES PATENT OFFICE.

ROBERT C. SCHEMML, OF UNION CITY, INDIANA, ASSIGNOR TO THE BACKSTAY MACHINE & LEATHER COMPANY, OF UNION CITY, INDIANA, A CORPORATION OF INDIANA.

FINISHING WELT AND PROCESS OF MAKING THE SAME.

Application filed May 22, 1924. Serial No. 715,164.

To all whom it may concern:

Be it known that I, ROBERT C. SCHEMML, a citizen of the United States, residing at Union City, in the county of Randolph and 5 State of Indiana, have invented certain new and useful Improvements in Finishing Welts and Processes of Making the Same; and I do hereby declare the following to be a full, clear, and exact description of the 10 invention, such as will enable others skilled in the art to which it appertains to make and use the same.

There are upon the market at the present time a variety of welts, gimps and bindings made of leather, leather substitutes and woven fabrics for use in trimming automobile bodies and tops, other vehicles, furniture, etc. Finishing welts of the character indicated are exemplified by U. S. Patents 20 Nos. 1,226,600 and 1,490,856, issued to the undersigned, assignor to The Backstay Machine and Leather Company, under the respective dates of May 15, 1917 and April 15, 1924.

25 In the production of welts or bindings and gimps of the character indicated, it is important that they possess great flexibility, thus enabling the trimmer to neatly and effectively turn corners when applying the same in operative positions.

30 Ordinarily trimming welts as applied to vehicle bodies and tops, are secured in position by tacks, and it is considered good taste and judgment to so arrange such attaching means that it is concealed from view by agency of the welt itself, this type of welt being known to the trade as blind nail welt.

35 There are instances also wherein independent and separable wires have been employed to render the welt relatively stiff in form, so that when shaped or molded into finished form it will adhere to such shape by virtue of the within contained or enfolded stiffening wires aforesaid. I know of no instance however, prior to my present invention, where stiffening wires have been actually woven into the body of the fabric from which finishing welts are manufactured, so as to constitute an inseparable 45 part of the fabric itself without in the leastwise increasing the bulk thereof, or altering its appearance when shaped into final marketable form. Neither have I

knowledge of any prior welt construction 55 wherein such interwoven wires have been employed to impart to finishing welts, gimps or bindings the exact degree of stiffness required under varying conditions, and wherein the material once formed, requires no other means whatever of retaining 60 it in the desired shape.

My present invention therefore has for an object the production of finishing welts, gimps and bindings, or other articles of 65 manufacture, made upon a fabric base, having at predetermined intervals interwoven metallic strips or strands of wire, preferably annealed and of a gauge corresponding with that of the fabric strands employed, so that when folded into final 70 finished form transversely across the wire strands aforesaid, the manufactured article will retain its shape by reason of the stiffening qualities of the wire so employed.

75 As a further object my present invention contemplates and provides for the manufacture of finishing welts of the character indicated, wherein the wire-contained woven-base material is treated and impregnated by a suitable leatherizing dope, and is finally given a surface graining or ornamentation in imitation of leather.

80 A further object of the present invention resides in a novel method of manufacturing 85 finishing welts consisting of weaving into the basic material stiffening wires at predetermined intervals to afford the desired degree of stiffness, impregnating the base with a suitable leatherizing compound, cutting the said basic material into suitable strips, and forming the latter into welts adapted to be retained in form by agency of the within-contained wire strands aforesaid.

90 95 With the foregoing and other objects in view the present invention will now be particularly described and later pointed out by the claims appended.

In the accompanying drawings which 100 form part of this application for Letters Patent, and whereon corresponding reference characters indicate like parts in the several views:

105 Figure 1 is a plan view of a woven fabric base or body material, suitable for the production of welts, gimps, bindings, or other articles of manufacture, and illustrating at

one end a portion thereof which has been treated with leatherizing dope and grained in imitation of leather;

Figure 2 is a fragmentary and relatively 5 enlarged plan view of the woven material, showing interwoven wire strands at predetermined intervals;

Figure 3 is also an enlarged view showing 10 in section the aforesaid material folded into one form of finishing welt; and

Figure 4 is a perspective view showing a 15 small portion of finishing welt finally folded at one end, and in process of folding at the other end, including concealed fastening means or tacks.

Reference being had to the drawings and numerals thereon, 1 indicates the warp or longitudinal strands, and 2 the interwoven weft or transverse strands of the welt-cloth 20 or basic material from which finishing welts or other articles of manufacture may be made, there being interwoven at predetermined distances weft strands of wire 3 as best shown by Figure 2, imparting to this 25 basic material a degree of stiffness in proportion to the selected frequency of the said wires 3. These bendable wires 3 may be arranged to run either longitudinally, or as shown, transversely, and are of a gauge corresponding 30 with that of the fabric or fibre strands 1, with which they cooperate to produce a uniformly flat woven base as and for the purposes indicated.

When desirable that the finished goods 35 should resemble in appearance leather, the basic welt-cloth aforesaid is impregnated in the ordinary and well understood manner with a suitable leatherizing compound, and is then suitably grained between graining 40 rollers as indicated at 4, Figure 1.

In the production of welt corresponding with Figures 3 and 4 for example, the basic material, arranged and treated substantially as aforesaid, is folded around a bead or roll 45 5 as shown by said figures. Suitable tacks such as 6 are then driven through the base of welt, the extended portion or tack-concealing flap of which is then folded upon the base portion as indicated by Figure 4 to 50 cover and conceal the attaching tack heads.

6. The transversely arranged wires 3 being thus bent and folded upon themselves as best shown by Figure 3, serve to retain the finished welt in its folded finished position 55 because of their stiffening properties, and it will be noted that the degree of stiffness or rigidity, to meet varying requirements, is regulated by the frequency with which wires 3 are woven into the fabric. If

60 greater stiffness is required a greater number of wires is employed; if less stiffness, then a lesser number of wires 3 than those illustrated in Figure 2 of the drawings.

The foregoing being a description of my 65 present invention in one form of embodi-

ment, it should be noted that I do not limit myself to the exact product set forth, nor to the method steps enumerated, but on the contrary lay claim to all products and methods of producing welts, gimp, and 70 bindings having a base formed of interwoven fabric and wire strands arranged and adapted to retain the parts in their proper relative positions after folding or forming.

Neither do I consider this invention limited in its scope and usefulness to the manufacture of welts, gimp, and bindings, but on the contrary claim all uses to which my improved material can be applied as for example the manufacture of certain interior fittings for closed automobiles, such as ash-receptacles, match-boxes, vanity-boxes, and appliances that can readily be shaped or formed, and retained in position by agency 80 of the stiffening wires aforesaid.

It should be understood that my improved welt-cloth is produced by intertwining or interlacing with the usual fibre strands, a suitable number of pliable wire strands to insure the proper degree of stiffness, so that when folded transversely across such wire strands, into the form of finishing welts, or other articles of manufacture, the said articles will retain their finished shape, or folded forms, by reason of the stiffening properties of the wire strands thus employed.

And, it will be further understood that use herein of the word "pliable" as applied to metallic or wire strands is intended to indicate a material such as annealed wire, or strip lead for example, which may be readily folded flatly upon itself, and when so folded will retain that folded form or position independent of other fastening means.

One satisfactory manner of producing welt-cloth of the character above indicated is that of interweaving warp and weft strands in the usual manner of making woven fabrics, except for a suitable number of transverse or weft strands of relatively soft annealed and therefore pliable wire which are substituted for a like number of fibre strands.

My present invention however is not limited to pliable metallic strands running in one direction only, because it is entirely within the spirit of this invention to run them in either or both directions, and to vary them in number with relation to that of the fibrous strands employed according to the degree of stiffness desired or required.

Having thus described my present invention what I now claim and desire to secure by Letters-Patent is:

1. A finishing welt of the blind-nail type including a base portion and a tack-concealing flap formed from a body strip having integrally embedded therein pliable metallic

strands extending into the tack-concealing flap and adapted to retain the latter in finished form when folded upon the base portion.

5. 2. A finishing welt of the blind-nail type including a base portion and a tack-concealing flap formed from a body strip having integrally embedded therein pliable wire strands extending into the tack-concealing

10 flap and adapted to retain the latter in finished form when folded upon the base portion.

15 3. A finishing welt of the blind-nail type including a base portion and a tack-concealing flap formed from a body strip having integrally embedded therein independent pliable metallic strands extending into the tack-concealing flap and adapted to retain the latter in finished form when folded upon

20 the base portion.

25 4. A finishing welt of the blind-nail type including a base portion and a tack-concealing flap formed from a body strip having interwoven therein independent parallel wire

strands extending into the tack-concealing 25 flap and adapted to retain the latter in finished form when folded upon the base portion.

30 5. A finishing welt of the blind-nail type including a base portion and a tack-concealing flap formed by a body strip reinforced throughout its entire width by interwoven independent wire strands extending into the tack-concealing flap and adapted to retain the latter in finished form when folded upon 35 the base portion.

35 6. A finishing welt of the blind-nail type including a base portion and a tack-concealing flap formed by a body strip reinforced throughout its entire width by interwoven 40 independent pliable wire strands at predetermined intervals extending into the tack-concealing flap and adapted to retain the latter in finished form when folded upon the base portion.

45 In testimony whereof I affix my signature.

ROBERT C. SCHEMML.
